UNITED STATES PATENT OFFICE

GEORGE EDWARD TAYLOR, OF LONDON, ENGLAND, ASSIGNOR TO AJAX ELECTRO-THERMIC CORPORATION, OF TRENTON, NEW JERSEY, A CORPORATION OF NEW JERSEY

HIGH FREQUENCY COIL FOR ELECTRIC INDUCTION FURNACES

Application filed July 5, 1928, Serial No. 290,400, and in Great Britain December 7, 1927.

My invention relates to induction electric furnaces in which the inductor is applied in a single layer about the molten metal and requires special cooling accommodation.

5 In electric induction furnaces energized by high frequency currents, the losses in the primary furnace coil may be a considerable proportion of the total energy applied to the coil. It is therefore of great importance that the 10 coil should be designed to reduce these losses to a minimum.

When conductors in the form of flat copper strips, such as are generally used in the furnace coil, carry high frequency currents, 15 the useful radial width is limited by the electrical phenomenon known as skin effect, and its resistance cannot be reduced by increasing the width of the conductor beyond a certain limit. It is also found that when the 20 conductors are in the form of a cylindrical helix, the distribution of the current is not uniform over the radial width of the conductor shown as edgewise wound, but is displaced towards the inner diameter of the helix.

25 It is therefore necessary that to reduce the resistance of a given coil the axial depth of the copper in the turns should be a maximum and the insulating and cooling space between the turns a minimum. If, however, 30 the axial depth of the copper is large, eddy currents are induced in it which may attain a considerable magnitude and cause an appreciable loss.

The object of the invention is to construct 35 a coil in such a manner as to reduce the various losses to a minimum and to provide means for effectively taking away the heat which may be generated in the coil.

Figure 1 is a fragmentary cross section of a 40 furnace to which my invention is applied.

Figures 2-5 illustrate examples of cross sections of conductors according to the invention.

Figure 1 is intended merely to show one 45 setting in which my invention appears in

which I have shown a crucible 1, separated by a space 2, from a lining 3 for an inductor helix of my invention and shown as of the form of Figure 5. The turns of the inductor are shown as insulated at *d*. 50

In Figure 2 the cylindrical helix consists of copper strip, wound radially, each turn comprising three conductors in parallel. The centre conductor *a* is wider than the other two *b'*, *b²*, its outer diameter projecting beyond the other conductors. This construction enables the heat generated in the coil to be readily transferred to the surrounding atmosphere. 55

The parallel conductors may be separated 60 by a slight coating of insulating varnish or strips of insulator in order to minimize the eddy current losses. Where used this varnish or insulating coating will be represented by division lines between the parallel conductors of the same turn. 65

Figure 3 is similar to Figure 1, but the conductor consists of two projecting strips *a'*, *a²* and three strips *b'*, *b²*, *b³* of less radial width.

The copper or other metallic strips may be 70 replaced by cables or tubes.

When it is desired to cool the coil by the flow of a cooling liquid or gas, the projecting conductors may be formed as a tube.

Figure 4 shows an example of this construction in which the radially extended conductor *c* is formed as a tube which is flattened at the part interposed between the strip conductors *b'*, *b²*. 75

The hollow portion of the conductor *c* has 80 an internal cross section suitable for containing the quantity of fluid required for carrying away the heat generated in the coil. It may have the same axial depth as each turn of the coil. 85

In Figure 5 three strip conductors *b'*, *b²*, *b³* and two tubes *c'*, *c²* are shown.

What I claim as new and desire to secure by Letters Patent is:—

1. In an electric inductor furnace, an in- 90

ductor coil comprising in each turn a tubular member flattened in one part to provide a solid radially inner conducting portion and a radially exterior hollow part to receive a cooling liquid.

- 5 2. An inductor coil comprising a plurality of adjacently located current-traversed conductors, and artificial cooling means co-extensive therewith and embodying a metal element having a fluid-traversed tubular portion and a fin portion operatively engaging the conductors.
- 10

GEORGE EDWARD TAYLOR.
